UNITED STATES PATENT OFFICE.

GEORGE E. BELCHER, OF STOUGHTON, MASSACHUSETTS.

LAST.

1,134,505.

Specification of Letters Patent.

Patented Apr. 6, 1915.

Application filed February 18, 1914. Serial No. 819,312.

To all whom it may concern:

Be it known that I, GEORGE E. BELCHER, a citizen of the United States, residing at Stoughton, county of Norfolk, Commonwealth of Massachusetts, have invented certain new and useful Improvements in Lasts, of which the following is a specification.

This invention relates to transversely divided lasts and particularly to a two-part last in which the last parts move on each other with a bearing formed by a dividing cut.

In the various shoe operations, the last is subjected to excessive pressure, which not only tends to split the last at the spindle socket but frequently breaks down the last at the union. It is to prevent this latter condition, that my present invention is particularly designed. As is well known a very considerable amount of this breaking down pressure is received by the pivot pin of the last union. Any slackness or play here, even the slightest, is therefore liable to destroy the predetermined adjustment of the last, by reason of the wood wearing away under the friction developed by the play of the parts of the union. When it is considered that the ordinary pivot pin is merely inserted through the hole at the link end and that neither pin nor hole are very accurately engaged for diameter it will be seen that considerable latitude for play is afforded at this point. This play is usually both vertical and lateral with its most pronounced tendency toward the lateral. The usual link simply works in a vertical kerf in the wood and has no lateral bearing. The usual pin simply passes through the hole in the link end and obviously can not assist, since the pin does not bear against the sides of the link. It has been proposed to use a pin of larger diameter to more nearly fit the hole in the link end. This expedient is open to the objection that it necessitates increasing the diameter of the hole in the link end and thereby weakens the link. Moreover the pin of larger diameter affords no more lateral bearing than does one of smaller size. This pin hole is used furthermore as a bearing on which the last turns on the jig in sawing the last. The small hole necessitated the use of a small jig pin with a constant tendency to accident or mistake. The larger bearing not only increases the strength of the jig but makes it more accurate against

possible eccentricities. To the end therefore of providing a form of last union in which all play will be obviated, I have devised my present invention. In it I use a novel form of pivot for the link which not only provides an enlarged bearing for the link end, but fits tightly against the sides of the link to prevent lateral play without interfering with the swinging motions of the link.

The construction and operation of my invention will be more fully disclosed in the specification which follows and in the drawings forming a part of that specification I have shown as an illustrative embodiment constructions which not only clearly illustrate the principles involved, but are in themselves forms proven satisfactory in practice and well adapted to the requirements of manufacture.

Throughout specification and drawings like reference numerals are correspondingly applied and in these drawings:

Figure 1 is a central longitudinal section through a last in accordance with my invention. Fig. 2 is a longitudinal section on the line 2—2 of Fig. 1. Fig. 3 is a transverse section on the line 3—3 of Fig. 1. Fig. 4 is a detail of the link and pivot therefor and Fig. 5 is a partial section showing a slightly modified construction.

I have indicated at 1 and 2 the fore and heel parts respectively of a divided last in which the last parts move on each other with a bearing formed by a curved dividing cut. The fore part 1 has a vertical kerf 3 and the heel part 2 a longitudinal bore 4 extending partially back toward the rear face of the heel part. The last union in the form shown consists of a link 5 which seats in the bore 4 at its rear end and is pinned in the heel part by a transverse pin 6. The link at its forward end is received and works in the kerf 3. At this end it has a transverse hole 7 let therethrough to receive the shank 8 of the pivot pin. The metal of the link on each side of the hole is cleared away as indicated at 20 and 21, Fig. 4. This enables the enlarged integral head 10 at one end of the shank and the enlarged detachable bearing sleeve 9 at the other end to come up tightly against the link end, and provide a lateral bearing effective to prevent play of the link. The head 10 and sleeve 9 are of substantially the same diameter and closely fill the transverse bore 13 of the toe part. This pro-

vides an enlarged bearing for the link without necessitating drilling the hole 7 of more than ordinary diameter which would be the case were a pin of the desired bearing used.

5 The possibilities of diameter of the hole 7 are limited to the diameter of the link itself and if the hole is made too large it is apparent that the link will be unduly weakened.

10 In assembling the shank of the pivot pin is inserted through the hole 7 in the forward end of the link until the shoulder formed by the head 10 seats tightly against the link in the cutout 20. The sleeve 9 is next slid on 15 to the projecting end of the shank until its inner end abuts the opposite face of the link at the cutout 21. When so set up the shank projects slightly beyond the outer end of the sleeve. This projecting end is then upset as 20 indicated at 14, Fig. 3. This locks the pin in place.

In Fig. 5 I have shown as a slightly modified construction two set screws 15 engaging the link on opposite sides. The screws each 25 consist of an enlarged bearing area 15¹ and a reduced link engaging point 15². The screws are entered from opposite sides of the last and turned in until their shouldered ends abut the flattened portions 20 and 21.

30 Various other modifications in the form and construction of my device may obviously be resorted to within the limits of the appended claims.

What I therefore claim and desire to secure by Letters Patent is:—

35 1. In a divided last comprising last parts and a union pivotally connecting said parts, and a pivot for said union comprising enlarged lateral bearings embedded in the 40 body of the last and an intermediate union supporting portion, said intermediate portion having a removable fit in one of said enlarged bearings.

45 2. In a divided last, a link having a hole let therethrough near one end and having the material at each end of said hole cleared away, a transverse pin lodged in one of the last parts and extending through said hole in the link and an enlarged bearing on said 50 pin arranged to be brought up close against both sides of said link at said cleared ends of the hole therethrough, a part of said en-

larged bearing having a removable fit on said pin.

3. In a divided last, a pivotal connection 55 comprising a link, a transverse pin lodged in one of the last parts and extending through a hole in the link, a head integral with said pin at one end and providing an enlarged bearing for said link at one side, 60 and a slideable sleeve on said pin at its opposite end and providing an enlarged bearing for said link at the other end.

4. In a divided last comprising last parts and a union pivotally connecting said parts, 65 a transverse pin lodged in one of the last parts and extending through a hole in the union and a fixed and a movable member on said pin affording enlarged lateral bearing for said union on both sides of said hole. 70

5. In a divided last comprising last parts and a union pivotally connecting said parts, a transverse pin lodged in one of the last parts and extending through a hole in the union, a head integral with said pin at one 75 end and providing an enlarged bearing for said union at one side, and a sleeve on said pin on its opposite end and providing an enlarged bearing for said union at the other end, said head and sleeve being of substantially the same diameter. 80

6. In a divided last comprising last parts and a union pivotally connecting said parts, a pivot for said union in one of said parts comprising a union supporting portion, and 85 a fixed and a movable portion associated with said union supporting portion and providing enlarged lateral bearing on both sides of said union.

7. In a divided last comprising last parts 90 and a union pivotally connecting said parts, a pivot for said union in one of said parts comprising a union supporting portion, and a fixed and a movable portion associated with said union supporting portion and providing 95 enlarged lateral bearing on both sides of said union, said movable portion receiving said link supporting portion.

In testimony whereof I affix my signature in presence of two witnesses.

GEORGE E. BELCHER.
